US00D481078S

(12) **United States Design Patent** (10) Patent No.: **US D481,078 S**
Stephan (45) Date of Patent: ** Oct. 21, 2003

(54) **MULTI-PANEL VIDEO DISPLAY UNIT
GAMING DEVICE**

DESCRIPTION

(75) Inventor: **Don Stephan**, Carson City, NV (US)

FIG. 1 illustrates a perspective view of a three-panel embodiment of a multi-panel gaming device according to the present invention.

(73) Assignee: **Innovative Gaming Corporation of America**, Las Vegas, NV (US)

FIG. 2 illustrates a front view of a three-panel embodiment of a multi-panel gaming device according to the present invention.

(**) Term: **14 Years**

FIG. 3 illustrates a top view of a three-panel embodiment of a multi-panel gaming device according to the present invention.

(21) Appl. No.: **29/129,487**

FIG. 4 illustrates a front view of a three-panel embodiment of a multi-panel gaming device illustrating the modular design of the gaming device having a computer enclosure and display unit and a wager and prize unit according to the present invention.

(22) Filed: **Sep. 14, 2000**

FIG. 5 illustrates a perspective view of a two-panel embodiment of a multi-panel gaming device according to the present invention.

(51) LOC (7) Cl. **21-03**

FIG. 6 illustrates a front view of a two-panel embodiment of a multi-panel gaming device according to the present invention.

(52) U.S. Cl. **D21/369**

FIG. 7 illustrates a top view of a two-panel embodiment of a multi-panel gaming device according to the present invention; and,

(58) Field of Search D14/306; D21/369-371,
D21/324-325; 463/16, 30-35, 45-47

FIG. 8 illustrates a front view of a two-panel embodiment of a multi-panel gaming device illustrating the modular design of the gaming device having a computer enclosure and display unit and a wager and prize unit according to the present invention.
